(57) **CLAIM**

The ornamental design for a wireless electronic security
device with surface ornamentation, as shown.

DESCRIPTION

FIG. 1 is a perspective view of a wireless electronic security
device with surface ornamentation showing the claimed
design;

FIG. 2 is a front elevational view thereof;

FIG. 3 is a left side elevational view thereof;

FIG. 4 is a right side elevational view thereof;

FIG. 5 is a back elevational view thereof;

FIG. 6 is a top plan view thereof; and,

FIG. 7 is a bottom plan view thereof.

The broken lines in the drawings show environmental structures
and form no part of the claimed design.
